OVERSHOE

Albert C. Kolb, La Crosse, Wis., assignor to La Crosse Rubber Mills Company, La Crosse, Wis.

Application March 6, 1952, Serial No. 18,797

Term of patent 14 years

(Cl. D7—4)

To all whom it may concern:

Be it known that I, Albert C. Kolb, a citizen of the United States, residing at La Crosse, county of La Crosse, and State of Wisconsin, have invented a new, original, and ornamental Design for an Overshoe, of which the following is a specification, reference being had to the accompanying drawing, forming a part thereof:

Fig. 1 is a perspective view of an overshoe embodying my new design with the upper portion thereof in closed position;

Fig. 2 is a side elevation on a reduced scale looking toward the opposite side from that seen in Fig. 1; and

Fig. 3 is a view similar to Fig. 1 showing the upper portion of the overshoe in open or out-spread position.

I claim:

The ornamental design for an overshoe, as shown and described.

ALBERT C. KOLB.
